UNITED STATES PATENT OFFICE.

WILLIAM H. PHELPS, OF FORT WAYNE, INDIANA.

SHOE BRAKE AND HEAD.

SPECIFICATION forming part of Letters Patent No. 608,623, dated August 9, 1898.

Application filed August 23, 1897. Serial No. 649,138. (No model.)

To all whom it may concern:

Be it known that I, WILLIAM H. PHELPS, a citizen of the United States, residing at Fort Wayne, in the county of Allen, in the State 5 of Indiana, have invented certain new and useful Improvements in Shoe Brakes and Heads; and I do hereby declare that the following is a full, clear, and exact description of the invention, which will enable others 10 skilled in the art to which it appertains to make and use the same, reference being had to the accompanying drawings, which form part of this specification.

My invention relates to improvements in 15 brake shoes and heads for railroad-cars and like vehicles.

It is well known to railroad men that the 20 wear to which brake-shoes are subjected, especially in loaded freight-trains when ascending or descending heavy grades, is very destructive to the shoes, indeed, so much so that on roads of very heavy grades in mountainous countries the shoes often have to be renewed upon nearly every trip; and the object of my invention is to provide a removable shoe which can be readily attached or detached from the brake-head by hand without the aid of tools, yet when in its seat is securely non-detachable by any jolting or jar- 25 ring of the train. The shoe is very simple in construction, is reversible, and can be attached and detached from the brake-head by any person without mechanical knowledge. I attain this object by the construction de- 30 scribed in the following specification and illustrated by the accompanying drawings, in which—

Figure 1 is a side view of the brake head and shoe attached to the brake-beam. Fig. 40 2 is a front view of Fig. 1. Fig. 3 is a detail plan of the brake-head. Fig. 4 is a longitudinal sectional view through the line xx , Fig. 5. Fig. 5 is a front view of the brake-head with the shoe removed. Fig. 6 is a detail plan 45 of the detachable shoe; Fig. 7, a side view of the same; Fig. 8, a front view of the pivoted key which fastens the shoe in the brake-head. Figs. 9 and 10 are plan and side views, respectively, of Fig. 8. Fig. 11 is a longitudinal central sectional view of the shoe brake and head with the parts in proper position, showing a modification of the manner of se-

curing the bolt upon which the locking-key is pivotally mounted.

Similar reference-numerals indicate like 55 parts throughout the several views.

1 is an ordinary brake-beam to which the brake-head 3 is secured by a proper bolt 2' through the perforation 2 in the head or other suitable manner, and 11 is a perforated lug 60 integral with the head, by which it is suspended from the car-sill in a well-known manner. The brake-head 3 has a concave face conforming approximately to the curvature of the wheel-tread and is provided on its 65 face with a longitudinal L-slot 5 and transverse slots or grooves 6 and 7. At the upper end of the brake-head is a slot 12, communicating at its lower end with the slot 6 and extending laterally from one side of the head 70 partly through it and outwardly at the top, as shown in Figs. 3 and 4. The shoe 4 has its inner face conformed to the face of the head 3 and its outer face to the curvature of the car-wheel tread, and on its inner face are two 75 T-shaped lugs 14 and 15, adapted to slidably enter the transverse slots 6 and 7 until they register with the longitudinal slot 5.

At the upper edge of the brake-head is a key 8, pivotally mounted in the slot 12 by a 80 bolt 18, inserted in the perforations 9 in the key and head, as shown in Figs. 4 and 8, and secured therein in any suitable manner. The perforation 9 through the key is out of the center of gravity and near the inner and upper 85 edges of the key, so that by its weight it will normally hang with its lower edge in the slot 6. The key 8 has also upon its outer edge an integral lug 10, and the upper inner edge is rounded to admit of its free pivotal move- 90 ment in the slot 12, and upon its lower edge it has a forwardly-projecting flange slightly serrated and adapted when the key is seated to project into the slot 6. The outer sides 16 and 17 of the lugs 14 and 15 are also serrated 95 in order to more securely retain the key from displacement by the jarring of the train or the upriding of the shoe. This construction of the serrated edges of the key and lugs is not indispensable and may be omitted. In- 100 stead of the perforation 9 extending through the head, as shown in Fig. 4, it need only pass partly through and have its other end flush with the face of the head, with the shoe ex-

tending partly or entirely above and covering the end of the bolt, as shown in Fig. 11, and by which construction it is obvious that the bolt will be effectually secured so long as 5 the shoe is in position on the head.

The mode of using the device is as follows: Taking hold of the lug 10, the key 8 is thrown up until the lower edge is completely out of the slot 6. The shoe-lugs 14 and 15 are 10 pushed laterally in the slots 6 and 7 until they register with the slot 5. The shoe will then readily drop until the lower lug rests in the end of the slot 5. Then throwing the key down the flange 13 will engage with the slot 15 6 against the lug of the shoe and securely fasten it within the head. To remove the shoe, throw up the key 8 and raise the shoe until the lugs 14 and 15 register with the transverse slot and pull it out the reverse of 20 the manner it was placed in position.

A shoe by this construction can be readily detached and another substituted without the use of any tool, as the engagement of the key with the top of the lug is not so close as 25 to prevent its elevation with the hands; but if it should stick by reason of dirt a slight blow with a link or coupler will loosen it. There are no nuts to loosen or bolts to remove or to be insecurely fastened by careless 30 train-hands, as the device is practically self-locking. The ends of the shoe are alike in construction, so that it makes no difference which end is used for the upper, and it can be reversed when desired.

35 I do not confine myself to the particular forms of the slots and lugs described, as it is obvious that they may be varied without departing from the scope of my invention.

Having thus described my invention, what

I claim as new, and desire to secure by Letters 40 Patent, is—

1. A brake-shoe having lugs as described, in combination with a brake-head provided with longitudinal and transverse intersecting slots, adapted to receive and engage said 45 brake-shoe lugs, and also provided with a slot 12 constructed as described; a key 8 pivotally mounted in said slot 12, and having upon its outer edge a lug 10 and upon its lower edge a forwardly-projecting flange 50 adapted when the key is seated to project into the upper transverse slot, and prevent the upward riding of the shoe; all arranged substantially as described.

2. A brake-shoe having T-headed lugs upon 55 its inner face with their outer edges serrated, combined with a brake-head having a face conforming to the inner face of the shoe, and provided with transverse grooves or slots, and intersecting a longitudinal slot, adapted 60 to receive and engage said lugs as described, and also provided at its upper part with a slot 12; a key 8 and secured therein by bolt 18, and having upon its outer edge a lug 10 and upon its lower edge a forwardly-projecting flange serrated upon its lower edge, and adapted when the key is seated to project into the upper transverse slot of the brake-head and detachably engage with the adjacent serrated edge of the upper lug; all arranged as described and shown.

Dated and signed at Fort Wayne on this 16th day of August, 1897.

WILLIAM H. PHELPS.
